SEWING MACHINE

Alfred R. Wood, Bridgeport, Conn., assignor to
The Singer Manufacturing Company, Elizabeth, N. J., a corporation of New Jersey

Application January 11, 1934, Serial No. 706,197

7 Claims. (Cl. 112—73)

This invention relates to sewing machines, more particularly of the type having stitch-forming mechanism, a work-clamp, and means including a feed-wheel or pattern-cam for relatively moving the stitch-forming mechanism and work-clamp to place the stitches in the desired order or arrangement. Such machines are commonly used in tacking and barring operations, attaching articles such as buttons and labels to fabrics, sewing buttonholes, etc. In such machines, and particularly in buttonhole sewing machines, it is desirable that provision be made for turning the feed-wheel or pattern-cam by hand to any position of its cycle, while the stitch-forming mechanism is at rest, so that in case of breakage of the sewing thread during a normal cycle of operations, the sewing operation may be re-started at the point of interruption and continued to the normal end of the cycle, without sewing over the entire pattern.

In machines having an over-running clutch or pawl-and-ratchet driving connection between the main-shaft and the feed-wheel, there is no difficulty in turning the feed-wheel forwardly by hand to any desired position, while the main-shaft is at rest. An over-running driving connection for the feed-wheel is objectionable, however, on account of the tendency of the feed-wheel to overthrow, making it necessary to frictionally load the feed-wheel by a braking device.

An object of the present invention is to provide a sewing machine of the type under consideration which requires no feed-wheel brake-band or like loading device and in which provision is made for the hand-turning of the feed-wheel to any desired position in its cycle, while the main-shaft is at rest, to enable the machine to be used for the repair of a previous imperfectly stitched buttonhole or other stitched article, without the necessity of sewing through an entire cycle of movement of the feed-wheel.

Another object of the invention is to provide the machine with manually controlled means for stopping the machine before it finishes its normal cycle of operations so that, in case of needle breakage, for example, the machine may be stopped to avoid damage to the work by the stump of the broken needle.

With the above and other objects in view, as will hereinafter appear, the invention comprises the devices, combinations, and arrangements of parts hereinafter set forth and illustrated in the accompanying drawings of a preferred embodiment of the invention, from which the several

features of the invention and the advantages attained thereby will be readily understood by those skilled in the art.

In the accompanying drawings, Fig. 1 is a right side elevation of a straight buttonhole sewing machine embodying the invention; the parts being in their normal positions of rest between stitching periods. Fig. 2 is a left side elevation of the machine. Fig. 3 is a horizontal section through the bracket-arm standard of the machine, showing the machine bed in plan. Fig. 4 is a side elevation of the manual control mechanism at the side of the sewing machine bracket-arm, as shown in Fig. 1, but with the parts in normal machine-running position. Fig. 4^a is an enlarged detail view of a portion of Fig. 4. Fig. 5 is a fragmentary horizontal section through the machine arm, Fig. 1 at about the level of the main-shaft. Fig. 6 is a fragmentary top-plan view of the pin-and-star-wheel drive for the feed-wheel or pattern-cam of the machine. Fig. 7 is a section on the line 7—7, Fig. 4. Fig. 8 is a rear end elevation of the machine. Fig. 9 is a section of the machine-frame on the line 9—9, Fig. 1, showing the driving and driven elements of the feed-wheel-coupling engaged in normal driving relation. Fig. 10 is a similar view with the elements of the coupling disengaged. Fig. 11 is a vertical sectional view on the line 11—11, Fig. 9. Fig. 12 is a perspective view of the feed-wheel-coupling operating rack. Fig. 13 is a similar view of the guide for such rack, and Fig. 14 is a perspective view of the driving-element of the coupling.

The machine-frame comprises the usual bed 1 and standard 2 of the overhanging bracket-arm 3 terminating in the head 4 in which is pivoted on the pins 5 the vibratory gate 6 for the reciprocating needle-bar 7 carrying the needle 8. The needle-bar 7 is reciprocated by the usual link-and-crank connection 9, 10, with the main-shaft 11 carrying at its rearwardly projecting end the tight-and-loose belt-pulleys 12 and 13, respectively, and a pinion 14 meshing with a stop-gear 15 of twice its diameter to which is fixed a conventional stop-cam 16, Fig. 8. Cooperating with the stop-cam 16 is the upwardly spring-pressed stop-plunger 17 carried by the stop-motion lever 18 mounted on trunnion-screws 19 for tilting movements between stopping and running positions, shown in full and dotted lines, respectively, in Fig. 2.

The stop-motion lever 18 has a forwardly extending arm 20 rigid with it and this arm 20 is pivotally connected at 21 to a vertical and up-

wardly spring-pressed rod 22 extending downwardly through the bed 1 and connected to a pedal-chain 23. A down-pull on the rod 22 tilts the stop-motion lever 18 to running position, in which position it is held by the spring-pressed latch-lever 24 which enters the side notch 25 in the rod 22. At the completion of a sewing period the latch-lever 24 is tripped to release the rod 22 by means of the usual tripping point 26, Fig. 3, 10 on the pattern-cam 27.

The driving belt 28 is under the control of the belt-shipper fork 29 fixed to the rearward end of a rearwardly spring-pressed slide-rod 30 mounted in one arm of a lever 31 fulcrumed at 32 on the standard 2. The other arm 33 of the lever carries a vertically adjustable pin 34 the lower end of which is in the path of travel of the belt-shipper tripping point 35 on the cam-disk 36 fixed to the vertical shaft 37 carrying the feed-wheel 27. A stop block 38, Fig. 1, secured to the lever-arm 33 engages the frame-bracket 39 to limit the movement of the lever 31 in one direction under the influence of its biasing spring 39.

The stop-motion lever 18 has an outwardly and upwardly curved arm 40 in which is fixed a horizontal latch-pin 41 cut away to form a tooth 42 adapted, in the motion of the stop-motion lever 18 from stopping position, Fig. 1, to running position, Fig. 4, to engage the tooth 43 on the block 44 fixed to the rod 30 and shift the rod 30 and belt-shipper fork 29 to running position, Fig. 4. Near the end of a sewing period the lever 31 is tilted by the tripping point 35 to disengage the tooth 43 from the tooth 42 and allow the spring-pressed rod 30 and belt-shipper fork 29 to carry the belt 28 to the loose pulley 13. The machine now coasts to final stopping position determined by engagement of the tripping point 26 on the feed-wheel 27 with the latch-lever 24 which is disengaged from the notch 25 in the vertical rod 22 secured to the arm 20 of the stop-motion lever 18. The stop-motion device and belt-shipper release above described is thus constructed substantially in accordance with the disclosures of the Allen et al. Patent No. 1,878,091, of Sept. 20, 1932, and the Allen Patent No. 1,659,937, of Feb. 21, 1928.

The work-clamp is of the usual construction shown, for example, in the patent to Wood, No. 1,613,634, of Jan. 11, 1927, and having the lower longitudinal slide-plate 45, Fig. 3, mounted in the cross-slide-plate 46; such slide-plates being actuated by the usual connections with the longitudinal and lateral feed-cam grooves 47 and 48, respectively, in the feed-wheel 27. The work is held on the slide-plate 45 by the upper rectangularly apertured clamping foot 49 carried by the usual downwardly spring-pressed clamp-lever 50 fulcrumed at 51 on a bracket 52 on a lateral extension 53 of the longitudinal slide-plate 45.

During a normal sewing period the feed-wheel shaft 37 is given a slow step-by-step turning movement by an accelerating and retarding or non-overthrow driving connection with the main-shaft. This connection preferably comprises a bevel-gear 54, Figs. 1 and 6, on the main-shaft 11 meshing with a gear 55 of double its pitch diameter carrying the diametrically opposed driving pins 56 working in radial slots in the star-wheel 57 fixed to the shaft 58 having at its upper end the usual gear-connections 59 with the needle-bar vibrating crank 60, such as disclosed in the Allen Patent No. 1,864,165, of June 21, 1932.

The shaft 58 carries at its lower end a gear 61, Figs. 1 and 5, which drives the gear 62 concen-

tric with and fixed to the pinion 63 meshing with the gear 64 fast on the feed-wheel shaft 37. By the means described the feed-wheel is positively geared to the main-shaft and there can be no overrunning of the feed-wheel during normal sewing operations. The driving connections are as effective in retarding the feed-wheel after the transmission thereto of a driving impulse, as they are in transmitting such driving impulse. Hence no frictional loading means are required for the feed-wheel to prevent overrunning of the latter.

There are times however, in the operation of the machine, when it is desirable to manually turn the feed-wheel forwardly independently of the main-shaft. This has heretofore been permitted by the one-way or overrunning clutch feed-wheel-driving connection commonly used and disclosed, for example, in the patents to Allen, No. 738,591, of Sept. 8, 1903, and No. 806,231, of Dec. 5, 1905.

According to the present improvement there is provided, in combination with the non-overrunning feed-wheel-driving mechanism, manually and instantaneously operable clutch means for disconnecting the feed-wheel from the main-shaft, to permit the feed-wheel to be turned by hand to any desired position while the stitch-forming mechanism is at rest. To this end, the gear 61 is slidably mounted on the shaft 58, Figs. 9, 10 and 11, and is formed with a hub having therein a diametral clutch slot 65 and urged upwardly by the spring 66 to embrace the diametral clutch pin 67 in the shaft 58.

Secured to the frame-arm 3 by the screw 68, Figs. 1, 9, 10 and 13, is the vertical leg 69 of an L-shaped bracket, the horizontal leg 70 of which is formed with an aperture 71 embracing the shaft 58. The vertical leg 69 of the L-shaped bracket is formed with a vertical guideway 72 for the vertical rack-bar 73 having a foot 74 formed with two spaced and downturned toes 75 engaging the upper face of the gear 61.

Slidably and rotatably journaled in an ear 76 on the L-shaped bracket 69, 70, is a manually operated rod 77 supported at its forward end in a bearing post 78 and formed with an operating handle 79. Fixed to the rearward end of the rod 77 is a long-faced pinion 80 which meshes with the rack 73. It will be evident that the operator may, by turning the handle 79 at any time, instantly rotate the rod 77 and pinion 80 to depress the gear 61 from the position shown in Fig. 9, to that shown in Figs. 10 and 11, in which the gear 61 and feed-wheel shaft 37 are de-clutched from the driving shaft 58 and may be turned by hand to any desired position. Upon release of the handle 79, the spring 66 automatically effects a recoupling of the gear 61 to its shaft 58, when the clutch pin 67 and clutch slot 65 are in register.

It may be here explained that to facilitate the hand-turning of the feed-wheel 27 when the main-shaft is stationary, there is provided a hand-lever 81, Fig. 3, which is loose on the feed-wheel shaft 37 and carries a spring-pressed pawl 82 in engagement with a ratchet-wheel 83 fixed to the shaft 37. The lever 81 has pivoted to it a handle 84.

There are times when it is desirable to stop the machine during a sewing period before the stitching cycle is completed. For example, in case of needle-breakage, it is desirable that the machine be stopped to prevent injury to the work by the stump of the needle. To this end means are provided whereby the operator may, at will, disen-

gage the tooth 43, Fig. 4, from the tooth 42, thereby permitting the spring-pressed rod 30 and belt-shipper fork 29 to carry the belt 28 onto the loose pulley 13; the stop-motion lever 40 and plunger 17 remaining in their tilted or running position, out of engagement with the stop-cam 16.

Pivoted on the pin 41, Fig. 7, are the legs of an inverted U-shaped lever 85 carrying an adjustable push-screw 86 the head 87 of which engages the upper inclined end of the block 44. The lever 85 is connected by a link 88 to an arm 89 freely mounted on and projecting outwardly from the rod 77 and confined between collars 90 on such rod. Thus the operator may, while the machine is running, push rearwardly upon the rod 77, Fig. 4, and rock the lever 85 on the pin 41 sufficiently to depress the block 44 and disengage its tooth 43 from the tooth 42, thereby freeing the belt-shipper 29 from the stop-motion lever 40 and allowing the belt-shipper to shift the belt onto the loose pulley 13. Because of the long face of the pinion 80, this endwise movement of the rod 77 does not disengage such pinion from the rack 73. A stop-collar 91 on the rod 77 is adapted to engage the bearing 76 and limit the rearward movement of the rod 77. A stop-pin 92 on the collar 91 is adapted to engage the arm 93 on the L-shaped bracket 69, 70, Fig. 10, and limit the turning movement of the rod 77.

Suppose that the machine has been stopped by the operator in the course of a sewing cycle, by tripping off the belt-shipper, because of a broken needle. The operator may turn the clutch control rod 77 to disconnect the gear 61 from the shaft 58 and uncouple the feed-wheel 27 from the main-shaft 11, whereupon the ratchet lever 81 may be oscillated by the operator to turn the feed-wheel ahead to its normal stopping position, or until the tripping point 26 on the feed-wheel engages the latch-lever 24 and releases the stop-motion lever 18. The work-clamp 45, 49 is now in normal starting position. The operator may then remove the broken needle and replace it with a new one. The operator may then further ratchet the feed-wheel forwardly until the work-clamp is carried to the position relative to the needle where the stitching was interrupted. By now grasping the laterally extending stud 94 or extension of the pin 41, the stop-motion lever 40 may be tilted to running position, carrying the belt-shipper with it. Thus the sewing may be restarted at or slightly ahead of the point of interruption, to avoid a gap in the stitching, and proceeds normally to the end of the sewing cycle.

In case of an interruption to the sewing due to thread breakage or exhaustion of the bobbin-thread supply, the machine may be permitted to run to the end of its cycle but without cutting the buttonhole. The operator may then re-thread the machine and ratchet the feed-wheel around to the point of interruption of the sewing and pull forwardly on the stud 94 to start the machine, whereupon the sewing is resumed and the partly finished buttonhole completed.

The belt-shipper rod 30 has fixed thereto a depending finger-piece 95 whereby the belt-shipper rod 30 may, if found desirable in practice for any reason, be pulled forwardly or re-set in running position, independently of the stop-motion lever 18.

The machine is, of course, equipped with the usual buttonhole slit cutter 95 having the usual manually interruptable operative connections, not shown, with the stop-motion-controlled cut-

ter-lever 96, substantially as disclosed in the Allen Patent No. 743,213, of Nov. 3, 1903.

Having thus set forth the nature of the invention, what I claim herein is:

1. A sewing machine having, in combination, stitch-forming mechanism, a work-clamp, means including a feed-wheel for relatively moving the stitch-forming mechanism and work-clamp to place the stitches in the desired order or arrangement, a main-shaft, a stop-motion device therefor, means driven by the main-shaft for accelerating and retarding the feed-wheel in imparting step-by-step movements thereto, manually operated means for uncoupling the feed-wheel from its driving means, and manually operated means for turning the feed-wheel to any desired position while the stitch-forming mechanism is at rest.

2. A sewing machine having, in combination, stitch-forming mechanism, a work-clamp, means including a feed-wheel for relatively moving the stitch-forming mechanism and work-clamp to place the stitches in the desired order or arrangement, a main-shaft, a stop-motion device therefor, a non-overrunning driving connection between the main-shaft and feed-wheel, manually and instantaneously operable clutch means for uncoupling the feed-wheel from the main-shaft to permit the feed-wheel to be turned by hand to any desired position while the stitch-forming mechanism is at rest.

3. A sewing machine having, in combination, stitch-forming mechanism, a work-clamp, means including a feed-wheel for relatively moving the stitch-forming mechanism and work-clamp to place the stitches in the desired order or arrangement, a main-shaft, a stop-motion device therefor, a pin and star-wheel driving connection between the main-shaft and feed-wheel, manually operable clutch means for uncoupling the feed-wheel from the main-shaft, and manually operated means for turning the feed-wheel to any desired position while the stitch-forming mechanism is at rest.

4. A sewing machine having, in combination, stitch-forming mechanism, a work-clamp, means including a feed-wheel for relatively moving the stitch-forming mechanism and work-clamp to place the stitches in the desired order or arrangement, a main-shaft, a stop motion device therefor, means including a system of reduction-gears for driving the feed-wheel in step-by-step fashion from the main-shaft, said means operating to hold back the feed-wheel from overthrow, manually operated means for uncoupling the feed-wheel from the main-shaft, and automatic means for re-coupling the feed-wheel and main-shaft.

5. A sewing machine having, in combination, stitch-forming mechanism, a work-clamp, means including a feed-wheel for relatively moving the stitch-forming mechanism and work-clamp to place the stitches in the desired order or arrangement, a main-shaft, a stop-motion device therefor, a non-overrunning driving connection between the main-shaft and feed-wheel, a manually operable rotatable and endwise slidably control-rod, means actuated by one of said movements of said rod to uncouple the feed-wheel from the main-shaft, and means actuated by the other of said movements of said rod to disconnect the machine from its source of power.

6. A sewing machine having a frame including a bed and an overhanging bracket-arm, stitch-

forming mechanism incorporated in said frame and including a reciprocating needle operating at the free end of said bracket-arm, a work-clamp, means including a feed-wheel for relatively moving the stitch-forming mechanism and work-clamp to place the stitches in the desired order or arrangement, a main-shaft connected to drive the stitch-forming mechanism and feed-wheel, a stop-motion device, a manually operated rod mounted at the side of the bracket-arm for rotary movement, a pinion on said rod, a rack meshing with said pinion, and means operated by said rack for uncoupling the feed-wheel from the main-shaft.

15 7. A sewing machine having, in combination,

stitch-forming mechanism, a work-clamp, means including a feed-wheel for relatively moving the stitch-forming mechanism and work-clamp to place the stitches in the desired order or arrangement, a main-shaft, a stop-motion device therefor, gear means including pin and star-wheel elements driven by the main-shaft for accelerating and retarding the feed-wheel in imparting step-by-step movements thereto, manually operated means for uncoupling the feed-wheel from said pin and star-wheel elements, and manually operated means for turning the feed-wheel to any desired position in its normal cycle of movement.

ALFRED R. WOOD. 15
